UNITED STATES PATENT OFFICE.

HERMAN C. BOEDICKER, OF MINNEAPOLIS, MINNESOTA.

COMBINATION-MACHINE FOR MAKING PHOTOPRINTS ON PRINTING-PLATES BY DIRECT CONTACT OR PROJECTION PRINTING.

1,327,752.

Specification of Letters Patent. Patented Jan. 13, 1920.

Application filed February 23, 1917. Serial No. 150,613.

To all whom it may concern:

Be it known that I, HERMAN C. BOEDICKER, a citizen of the United States, and a resident of Minneapolis, in the county of 5 Hennepin and State of Minnesota, have invented certain new and useful Improvements in Combination-Machines for Making Photoprints on Printing-Plates by Direct Contact or Projection Printing, of 10 which the following is a specification.

The machine described in this specification resembles, somewhat, the one described in my co-pending application Serial No. 56,931, filed October 20, 1915, and entitled 15 "Art of making photo prints on printing plates."

However, the machine described in the prior application can be used only for projection printing and I have determined that, 20 while a machine of that class has a great commercial value, yet the field for a machine which will make the photo prints by direct contact printing is much greater, and I have accordingly devised a machine that 25 can readily be used for making photo prints by both methods.

It is to be understood that this machine performs the step and repeat function described in my prior application, so that 30 multiple prints can be made on the single printing plate from a single printing surface, such as a negative, and that prints can be made from different negatives on the same printing plate, all of these operations being accomplished in absolute register.

One object of my invention is to provide simple and efficient means for printing, either by direct contact or by projection, 40 from the negative on a printing plate.

Another object of my invention is to provide certain devices that can be readily removed from the machine or can be readily transferred from one position to another.

Another object of my invention is to provide means for readily bringing a negative into absolute contact with a printing plate.

Another object of my invention is to provide means for locating on the machine itself, any certain position so that the machine may quickly and positively be returned to this position for a second printing operation.

With these and incidental objects in view,

the invention consists of certain novel features of construction and combination of parts, the essential elements of which are hereinafter described with reference to the drawings which accompany and form a part of this specification.

In the drawings, Figure 1 is a side elevation of my improved machine; Fig. 2 is a plan view of the same; Fig. 3 is an end view of the machine; Fig. 4 is a section taken on the line 4—4, Fig. 3; Fig. 5 is a fragmentary plan view of the hood connection with negative holder and lamp house, Fig. 11; Fig. 6 is an enlarged detail of the supporting rollers shown as a section taken on the line 6—6, Fig. 1; Fig. 7 is an enlarged detail of the locating means shown in Fig. 4; Fig. 8 is a front view of the negative holder; Fig. 9 is a section taken on the line 9—9, Fig. 8; Fig. 10 is a detail of the angular adjustment means 75 embodied in the negative holder; Fig. 11 is a side elevation of the lamp, lens, and condenser used on the machine for projection printing; Fig. 12 is a similar view of the machine with the lens and condenser removed and the lamp positioned for direct contact printing, and Fig. 13 is a section taken on the line 13—13, Fig. 11.

The means used for positioning the lamp, condenser, lens, etc., is similar to that disclosed in my copending application heretofore mentioned, and will be summarized herein only brief.

A pair of true. 1 Fig. 1 support on the vibration absorbing means 2, a base 3 which 90 carries a magnetic board 4' for holding print plates similar to the one described in my co-pending application, Serial No. 114,874, filed August 14, 1916, and entitled "Printing plate holding device."

The base 3 also supports on tracks 4, by rollers 5, better shown in Fig. 6, a frame 6 built of structural shapes and carrying thereon a table 7 which is hung by the cables 8 passing over pulleys 9, and counter- 100 balanced by the weights 10.

This table 7 carries on the ways 11, Fig. 2, a plate 12 on which is slidably mounted a lamp house 13, condenser 14, lens 15.

The slide connection of these parts is 105 better shown in Figs. 11 and 13.

To give vertical adjustment of the table 7, a hand wheel 16 is provided for turning the

shaft 17, Fig. 2, which, by beveled gears 18, shaft 19, worm and worm gears 20, and shaft 21 rotates pinions 22 along the vertical racks 23, better shown in Fig. 3.

5 To give longitudinal adjustment of the frame 6, the hand wheel 24, Fig. 1, actuates the gears 25 which travel along the horizontal rack 26, Figs. 1 and 2.

10 For transverse adjustment of the plate 12 on the table 7, the hand wheel 27, Fig. 1, turns the screw 28 directly, and through beveled gears 29, shaft 30, beveled gears 31, turns the screw 32, and these screws 28 and 32 respectively, co-acting with the nuts 33 and 34, carried by the plate 12, serve to adjust the plate 12 transversely on the table 7.

15 The plate 12 is provided with a T slot 35, better shown in Fig. 13, and the lens, negative holder, condenser and lamp are all provided with T bolts 36 and may be slidably adjusted, as plainly shown in Figs. 11 and 13, longitudinally on the plate 12.

20 In Figs. 1 and 2 I have shown a lamp, lamp house, condenser, lens and bellows of the same general style as that shown and described in my first application aforesaid, in order to show the advantages of my present construction.

25 30 While I may use on the machine herein described, these parts, as shown in Figs. 1 and 2, I prefer to use a different construction of lamp and lamp house as shown in Figs. 5, 11 and 12.

35 The lamp 37, Fig. 11 is entirely inclosed except for the projection aperture at 38 and carries at 38 a pair of in-turned angles 39, Fig. 5.

40 A condenser holder 40, Figs. 5 and 11, also carries a pair of oppositely disposed in-turned angles 41, and a hood 42 is provided with flanges 43 at one end and 44 at the other end to slide into the grooves formed by these in-turned angles.

45 50 Suitable inlet 45 and outlet 46 for air, are provided in any suitable manner so that the hood may be self-ventilating, to carry away heat from the lamp without losing any light through the ventilator; as the lamp must be focused with the condenser in accordance with the focusing of the lens, the hood 42 is formed in two parts, telescoping together at 42', Fig. 12.

55 60 A similar sliding joint connection is provided between the negative holder and the bellows 48.

With the apparatus disposed, as shown in Fig. 11 if it is desired to make prints by contact printing, it is only necessary to slide 65 the T bolt, carried by the lens holder, forwardly out of its slot, lift the slidable end of the bellows from its co-acting joint in the front side of the negative holder, slide the negative holder out of the slot, lift the hood 42 upwardly out of its slot joints, and re-

move the condenser 40, then replace the negative holder 47 in a reversed position, slide the hood 42 in engagement with its co-acting sliding joint carried by the lamp at 39, and with its co-acting sliding joint carried by what is now the rear side of the negative holder, and which formerly received the large end of the bellows.

The apparatus is then ready for direct contact printing and, as shown in Fig. 12, the negative 49 can be brought up into direct contact with the plate supported on the magnetic board 4.

The negative holder 47, shown in detail in Figs. 8 and 9, has adjustment means 50, better shown in Fig. 10, for angularly positioning the negative.

The negative comprises a beveled glass or other transparent material 51, on which is carried an actual photographic film from which the print is made.

It is to be noted that the lower edge of the beveled glass rests in a slot 52 carried by the negative holder, while the top of the beveled glass is maintained in its proper position by spring clips 53 so that the face 54 of the negative is carried in front of all mechanism of the negative holder, and can thus be brought directly into contact with the printing plate.

In this art it is quite essential for rapid work to be able to make a positive location of the positions of the various adjustable parts of the machine so that any position in which the machine has been operated on the plate can be duplicated at will so as to secure points in register.

It is also advantageous to be able to make a print on a large sized printing plate, to measure off directly on the machine a number of spaces, vertically and horizontally, a definite distance from the first exposure, and to be able to set the machine quickly at these various locations so that a number of exposures may be made on the plate at absolutely definite locations on the plate.

To accomplish both of these results, I provide a set of clips 55, Fig. 4, which may be clamped onto the channel members or angle members of the frame at any desired location by the screws 56.

The co-acting frame members carry a spring controlled indicating finger 57.

It is apparent that if the machine is adjusted in one position and the clip 55 is placed on the frame as shown in Fig. 7, in line with the indicating finger, that this particular adjustment can be repeated with great accuracy whenever desired; also if it is desired to not only repeat this particular position, but also to move quickly to a position at a definite distance above the one located, for instance, it is only necessary to place a second clip 55 along the channel member above the first clip and locate it ac-

curately with a pair of dividers or ruler from the first clip and that the machine can be quickly adjusted from one to the other of the positions.

5 It is of great importance in operating a machine of this class that the plate 12, Figs. 1 and 3, be moved in a rectilinear manner in all adjustments of the machine.

Thus the machine provides for three directions of adjustment and these directions must correspond to the planes bounding a cube or rectangular block whose angles are of ninety degrees.

For this reason it is of utmost importance that the ways in which the plate 12 slides transversely are horizontal at all times, that the vertical racks 23 are truly vertical and that the longitudinal rack 26 is absolutely horizontal and parallel to the longitudinal frame members of the machine base.

20 It is a simple matter to build the track 26 to meet its requirements, but the vertical members of the frame are subject to more or less distortion, and for this reason I have provided adjustment rods.

25 Four rods 58, Figs. 1 and 3, are provided each having an eye 59, Fig. 1, at one end and terminating in threaded end 60 at the other extremity which passes through an aperture carried by the extension 61 of the frame.

30 By means of a pair of nuts 62 and 62, one positioned on either side of the plate, these rods may be adjusted so as to draw the frame into a truly vertical position as viewed in Fig. 3.

35 Similarly four adjusting rods 64, Fig. 1, are provided to aline the frame vertically as viewed in Fig. 1.

40 The upper ends of these rods are preferably bent and fastened to the frame of the machine at 65 in any suitable manner, and the other ends are threaded at 66, and a pair of nuts 67 and 68, positioned on either side 45 of the plate of the frame through which the rod passes, provides for this adjustment.

50 Similarly the spacing rods 69 and 70 are each provided with a pair of nuts positioned on either side of the rear engagement point 55 with the frame at 71 and 72 respectively.

55 While I have described my invention and illustrated it in several designs, I do not wish it understood that I limit myself to these constructions, as the application of my invention may be varied in many ways within the scope of the following claims.

Claims:

1. In a combination machine for making photo prints on printing plates, the combination of a base, vibration absorbing means supporting said base, a plate supported on said base and having means of adjustment longitudinally, vertically, and transversely thereof, a lamp, a hood, a condenser, a negative holder, a bellows, and a lens slidably

60 mounted in said plate, said negative holder having means of engagement on one side thereof with said bellows, or said hood.

2. In a negative holder for machines for making photo prints on printing plates, the 70 combination of a frame for receiving therein a transparent plate having a beveled edge, and means for clamping said transparent plate to said frame so the front surface of said plate is forward of all means of engagement with said frame.

3. In a negative holder for machines for making photo prints on printing plates, the combination of a frame rotatably mounted, a transparent plate, and means of engaging 80 said transparent plate with said frame intermediate of the faces of said plate.

4. The combination, in a negative holder, of a rotatably mounted negative frame, a glass plate having two edges thereof beveled 85 and a notch in the lower side of said frame for receiving one of said beveled edges, with the forward surface of said plate extending forwardly of said frame, and spring clips for engaging the other beveled edge of said 90 plate.

5. In a combination machine for making photo prints on printing plates by direct contact or projecting printing, the combination of a base, vibration absorbing means 95 supporting said base, a table carried on said base and adjustable therewith vertically, longitudinally, and transversely, a board for holding printing plates mounted on said base, a lamp, a condenser, a negative holder 100 and a lens slidably mounted on said table, a hood slidably mounted between said lamp and said condenser and adapted to be slidably mounted between said lamp and said negative holder, and a telescoping extension 105 carried in said hood for focusing said lamp on said condenser.

6. In an adjustable table for making photo prints on printing plates, the combination of a lamp, a condenser, a negative holder 110 and a lens all slidably mounted in said table, a hood slidably engageable with said lamp and said condenser and having an extensible portion therein to allow the focusing of said lamp on said condenser, a bellows slidably mounted on said negative holder, said slidable means on said negative holder being also adapted to engage with the slidable means whereby said hood engages with said condenser, a beveled plate glass carried by 120 said negative holder on the opposite side from said slidable engagement means to receive thereon a transferred negative film.

7. In an adjustable table for making photo prints on printing plates, the combination 125 of a lamp, a condenser, a negative holder, and a lens, all slidably mounted in said table, a hood slidably engageable with said lamp and said condenser, and removable therefrom to allow visual registration of a 130

negative held in said negative holder with a plate on which the print is to be made from the negative held in said negative holder.

- 5 8. In an adjustable table for making photo prints on printing plates, the combination of a lamp, a condenser, a negative holder, and a lens, all slidably mounted in said table, a hood slidably engageable with said lamp and said condenser and having an extensible portion therein to allow the focusing of said lamp on said condenser, and bellows slidably mounted on said negative holder, said slidable means on said negative holder being also adapted to engage with

the slidable means whereby said hood engages with said condenser.

9. In a combination machine for making photo prints on printing plates by projection or direct contact, the combination of 20 an adjustable table, a lamp, a condenser, a negative holder, and a lens, all adjustably and detachably mounted on said table, a printing plate holder, and means for adjusting the devices carried by said table for projection printing or for direct contact printing on a printing plate held by said printing plate holder.

HERMAN C. BOEDICKER.
